SCAFFOLD JOINT

Charles H. Anderson, Downey, Calif.

Application May 7, 1934, Serial No. 724,255

10 Claims. (Cl. 304—40)

This invention relates to adjustable scaffolds and has particular reference to means for joining together and bracing sections of such scaffold.

5 The general object of my invention is to provide an improved scaffold of simplicity, ease of operation and economical to manufacture and install.

To this end, the invention consists in the combinations and advantageous features hereinafter fully described and illustrated in the accompanying drawings, of which:

Fig. 1 is a fragmentary elevation, partly in section, of a scaffold joint embodying the invention,

Fig. 2 is a substantially corresponding view showing the members of the joint partly separated,

Fig. 3 is a similar view, of a slightly modified structure, and Figs. 4 to 8 illustrate further modifications the importance of which will presently be described.

The structure of my invention comprises vertical tube sections 1 and 2, seated in a sleeve 3. On the section 1 is securely fastened a bracket 4, which comes to rest on the sleeve when the section is pushed into the sleeve. The lower section 2 may, at the bottom, carry a similar bracket 4 for seating in an additional sleeve 3, and it is made with a fixed collar 5 on which the sleeve, and in turn the upper section, is supported. The top of the upper section 1 may be similarly fitted to carry the scaffold upward. By adding section upon section, in this manner, it is possible to raise the scaffold of my invention to reach the various stories of the building which it is designed to serve.

The bracket 4 is shown made with laterally projecting head 4^a, and this head is perforated 40 to form a sleeve which may be substantially like the sleeve 3 and may function in the same manner to support horizontal sections. Or the sleeve may be positioned diagonally, as indicated at 6^a in Fig. 2, to support tubular braces (not shown).

45 The bracket 4 is also shown provided at one side, adjacent the sleeve 4^a, with a pendent apron 4^b, and this apron is spaced away from the tube section 1 far enough to slide down along the outer surface of the sleeve 3, when the parts are assembled.

A perforation 7 extends transversely through the section 1 and the apron 4^b, and this perforation is positioned to register with a perforation 3^a of the sleeve when the parts are assembled, 55 whereupon a key 9 is inserted through these

aligned perforations. This key is made with a laterally projecting cam 9^a which, when the key is inserted, is free to pass through notches 3^b and 7^a of the sleeve and tube section respectively. It is noticed that this cam lodges within the tube section when the key is fully inserted, whereupon the key is given a one-half turn to bring the cam out of registration with these key hole notches. The key is shown made with a handle 9^b extending laterally in the direction of the cam. 60 Because the key notches are at the top of the key hole, this key must be inserted with the cam and handle upwardly directed, as indicated in dotted outline. And when subsequently the key is turned downward, it is seen that the weight 65 of the pendant handle 9^b maintains the key in this position and the parts rigidly locked together.

The upper end of the sleeve is shown made with a lug 3^c, which is shaped to engage a notch 4^c in the bracket 4, thereby to maintain the tube section unturned in the sleeve while the two remain assembled.

A second key perforation is shown provided at the lower end of the sleeve for registration with a key perforation 2^a at the top of the section 2. 75 And a key 10, substantially like the key 9, is similarly insertable at this point firmly to lock these parts together.

The diagonal sleeve 6^a is shown made with similar key perforations 6^b, and such key holes 80 are also provided in the sleeve 4^a, all to serve the same function.

When tubular sections of desired lengths are provided, it is seen that scaffolds of any required proportions may be assembled and rigidly locked 90 together, complete with the angular braces necessary to provide a strong and rigid structure.

The keys 9 and 10 are simple to manufacture and securely held in place by the weight of their own handles. When the scaffold is fully erected, the pressure on these keys is so heavy that considerable force is necessary to turn the keys, making their use entirely safe. Should it, however, be objected, that a key accidentally or maliciously might be turned and withdrawn, it is 95 possible to provide other locking means, such as shown in Fig. 4.

In this case, a bolt 11 is employed, and this bolt is made with a reduced portion, or pilot 11^a, seated in the wall of the sleeve 14, and in the 100 apron of the bracket 13. The body portion of the bolt is, directly behind this pilot, made with screw threads engaging a threaded perforation in one side of the tubular section 12. The end 105 of the bolt is shown squared to receive a wrench. 110

When this bolt is tightened, it functions in the same manner that the keys operate. The head of the bracket 13 is shown fitted with a set screw 15 for fastening crosswise members, but it may, of course, be made with key holes for engagement by keys as above described.

The foregoing description covers simple and efficient means for joining horizontal and vertical sections of a demountable, tubular scaffold, as well as means for supporting diagonal braces to strengthen the structure. The method usually followed, in erecting scaffolds of this type, is to start at the bottom and to assemble section upon section as required to build or repair each succeeding story of a building. When the work on one floor is completed, the next higher scaffold section is assembled to reach above this story, and the loosely laid plank flooring of the scaffold is picked up to form the scaffold floor at the next higher story, all as very familiar to those versed in the art.

It is customary, at least in larger building projects, to provide an elevator for raising material to each new story to be added, and the device 25 of my invention lends itself admirably to the embodiment of such elevator, as will now be described and as illustrated in Figs. 6 to 8.

The vertical tube sections 1 and 2 may remain as described, and no change in sleeve 3 is necessary. The bracket 4 alone is modified, as indicated at 20, by adding a lug 20^a, in which are seated axially aligned pilots 20^b, 20^c, supporting elevator guide sections 21 and 22 in parallel relation to the vertical scaffold sections 1 and 2. The 35 laterally projecting head 20^d may remain exactly like the heads 4^a or 6^a. In other words, the only modification of the device is the addition of the lug 20^a for supporting the elevator guides 21 and 22.

40 In Fig. 7, two of these guides are shown provided. The elevator cage, or platform 23 is shown made with wheels 24, riding on the guides to reduce friction, and these wheels are mounted at the elevator corners in any suitable manner, as by brackets 25, secured to the elevator frame 26. The exact shape of the bracket lug 20^a is immaterial, it being only important that the peripheral outline of this lug lies in continuation of the guide sections, in order that there may be no break or interruption in the smooth guiding surface. The construction shown has the advantage that the guide sections merely need to be dropped in position on the pilots, to become securely locked in place.

55 From this it is seen, that an elevator may be supported and guided at any place along the scaffold of my invention merely by adding a lug, or its mechanical equivalent, to one of the members combining to form the structure of my invention. While this lug is shown added to the bracket 4, it may be incorporated in the sleeve 3 or in the collar 5, if preferred.

I claim:

60 1. In a scaffold, a sleeve made with key holes, tubular sections insertable in said sleeve and having key holes for registration with the key holes of the sleeve, and keys insertable through said key holes in one position and rotatable to a position of locking the sections in the sleeve and the keys against withdrawal.

65 2. In a scaffold, a sleeve made with key holes, tubular sections insertable in said sleeve and having key holes for registration with the key holes of the sleeve, members on said sections engaging the ends of the sleeve to arrest the movement of

the sections into the sleeve, and keys insertable through said key holes in one position and rotatable to a position of locking the sections in the sleeve and the keys against withdrawal.

70 3. In a scaffold, a sleeve made with key holes, 80 tubular sections insertable in said sleeve and having key holes for registration with the key holes of the sleeve, said sleeve and sections having interengaging portions preventing relative rotation of the parts, and keys insertable through said key holes in one position and rotatable to a position of locking the sections in the sleeve and the keys against withdrawal.

75 4. In a joint, a transversely perforated sleeve, 85 a tubular section insertable in the top of said sleeve and having a transverse perforation, a member on said section for arresting its insertion, said member having a transversely perforated apron spaced to slide along the outer surface of the sleeve, and a member seatable in said perforations to lock the parts rigidly together.

80 5. A sleeve transversely perforated near each end, tubular sections insertable in the sleeve from the ends and each made with transverse perforations for registration with the sleeve perforations, 100 one section having a fixed bracket terminating in a similar sleeve angularly positioned relative to the first sleeve and provided with a perforated apron fitting the outer surface of the first sleeve, and means engaging the perforations of the first 105 sleeve the sections and the said apron for locking said parts together.

85 6. In a scaffold, a tubular member, a tubular section slidable into said member, a tube carrying bracket rigidly mounted on said section for 110 limiting its insertion into said member and made with an apron fitting the outer surface of the member, the member, section and apron having transverse perforations for registration when the parts are assembled, and means engaging the 115 perforations to lock all said parts rigidly together.

90 7. In a scaffold, a tubular member, a tubular section slidable into said member, a tube carrying bracket rigidly mounted on said section and 120 made with an apron fitting the outer surface of the member, the member section and apron having transverse perforations for registration when the parts are assembled, and means engaging 125 said perforations to lock all said parts rigidly together, the tube of said bracket being shaped and fitted like the said tubular member to support other similar sections.

95 8. In a scaffold, a sleeve made with a key hole at each end, a tubular section insertable in said 130 sleeve and having a key hole for registration with one of the sleeve key holes, a member on said section for limiting the insertion of the section to bring said key holes in line, said member provided on one side with a similar sleeve angularly 135 positioned relative to the tube sections and having a lateral projection shaped to support elevator guides in parallel relation to said sections, and means insertable in said aligned key holes to lock the sections in position in the sleeve. 140

100 9. In a scaffold, a sleeve made with transverse perforations at each end, tubular sections insertable in said sleeve and each having a perforation for registration with the sleeve perforations, a member on each section limiting the insertion of the section to align said perforations and shaped to prevent rotation of the sections in the sleeve to disturb such alignment, said member having a lateral projection shaped to support 145 elevator guides in axial alignment parallel with 150

the sections, and means insertable in said aligned perforations to lock the sections in position in the sleeve.

10. In a scaffold, sleeves having each a transverse perforation at each end, tubular sections seatable in said sleeves and having at each end a transverse perforation for registration with the sleeve perforations and a member at each end for

limiting the seating of the sections to bring said perforations in line, the member at one end of each section having on one side a lateral projection fitted to support elevator guides in axial alignment and in parallel relation to said tubular sections, and means seatable in the aligned perforations for locking the sections in the sleeve.
